UNITED STATES PATENT OFFICE.

HOWARD SMALL, OF WYNCOTE, PENNSYLVANIA.

DESIGN FOR AN ELECTRIC-SWITCH FACE PLATE OR TRIMMING.

44,454.

Specification for Design.

Patented Aug. 5, 1913.

Application filed May 13, 1913. Serial No. 767,444. Term of patent 14 years.

To all whom it may concern:

Be it known that I, HOWARD SMALL, a citizen of the United States, and a resident of Wyncote, in the county of Montgomery and State of Pennsylvania, have invented a new, original, and ornamental Design for an Electric-Switch Face Plate or Trimming, of which the following is a specification, reference being had to the accompanying drawing, forming part hereof.

Figure 1 is a plan view and Fig. 2 is an edge view of an electric switch face plate or trimming, showing my new design.

I claim:

The ornamental design for an electric switch face plate or trimming, as shown.

HOWARD SMALL.
